UNITED STATES PATENT OFFICE.

THOMAS R. KENNEDY AND EDWARD J. KING, OF ROCHESTER, NEW YORK,
ASSIGNORS TO CO-OPERATIVE FOUNDRY COMPANY, OF ROCHESTER,
NEW YORK, A CORPORATION OF NEW YORK.

DESIGN FOR A HEATING-STOVE.

SPECIFICATION forming part of Design No. 36,157, dated December 9, 1902.

Application filed August 30, 1902. Serial No. 121,699. Term of patent 7 years.

To all whom it may concern:

Be it known that we, THOMAS R. KENNEDY and EDWARD J. KING, citizens of the United States, and residents of Rochester, in the county of Monroe and State of New York, have invented and produced a new, original, and ornamental Design for Heating-Stoves, of which the following is a specification, reference being had to the accompanying drawings, forming part thereof.

The illustration is a perspective view of a heating-stove embodying our new design.

The leading feature of our design consists of the general outline or contour of the stove as a whole and to the surface ornamentation application to the several parts thereof.

A indicates the base of the stove, which is substantially rectangular, having the curved ornamental legs 1 at the corners and provided at the sides with the large scroll ornaments 2, extending from the corners above the legs 1 to the scroll design 3 at the center. The sides of the base curve inwardly at their upper edges, and between the scrolls 2 at the corners these portions are also provided with ribs 4, and between the latter are small ornamental panels 5.

The ash-pit section B is provided at the front with the door 6, having a foot-rest embodying the ends 7, provided with scroll ornamentation, as shown, and the lower outwardly-extending portion 8, above which will be seen the damper-openings 9. The corners of the section are decorated with a scroll-and-leaf ornamentation 10, while at the sides are the foot-rests 11, provided with the central scroll 12 in relief. Arranged above the ash-pit section and at the forward side of the stove is an apron 13, having the corners rounded and provided with the plain depending flange, as shown.

The body of the stove (indicated by C) is

provided at the front with the upper and lower double fire-pot doors 14 and 15, respectively, and at the sides with corresponding doors 16 and 17, all of said doors having the mica panels, and the upper ones at the front and sides are ornamented with the spiral scrolls 18, while the corresponding lower doors are provided with the scroll 19. Between the upper and lower doors is a narrow band or zone decorated with the scroll-and-leaf design 30. At the forward corners the body is provided with the outwardly-extending ornaments 20 of filigree-work.

The top section D, surmounting the body of the stove, has the rounding upper surface and corners, forming a depending edge 21, above which the section is decorated with the scrolls 22 at the corners, connected by a band 23 in relief. Below the edge 21 the section is recessed or curved inwardly, forming niches at the center of the sides, and at each side of which the corners extend downwardly and are decorated with the design 24. Between the corners the body of the stove is rounded inwardly above the upper fire-pot doors, as indicated by 25, said rounded portions having the mica openings shown.

26 indicates the reservoir-cover arranged at the top of the section D, said cover being rounded and decorated with the scroll ornaments 27 in relief and the ornamental design 28, arranged between them.

Having described our design, what we desire to secure by Letters Patent is—

The ornamental design for a heating-stove substantially as herein shown and described.

THOMAS R. KENNEDY.
EDWARD J. KING.
